UNITED STATES PATENT OFFICE.

MATTHEW P. ELLIOT, OF CRYSTAL CITY, MISSOURI.

FURNACE FOR HEATING STEAM-BOILERS.

SPECIFICATION forming part of Letters Patent No. 331,287, dated December 1, 1885.

Application filed June 20, 1885. Serial No. 169,269. (No model.)

To all whom it may concern:

Be it known that I, MATTHEW P. ELLIOT, a citizen of the United States, residing at Crystal City, in the State of Missouri, have invented a new and useful Improvement in Furnaces for Heating Steam-Boilers, of which the following is a full, clear, and exact description, reference being had to the accompanying drawings, in which—

10 Figure 1 is a vertical longitudinal section on line 1 1 of Fig. 2, showing an arrangement of devices for carrying out the principles of my invention; Fig. 2, a horizontal section of the same on line 2 2 of Fig. 1; Fig. 3, a vertical transverse section of the same on line 3 3 of Fig. 1; Fig. 4, a vertical transverse section of the same on line 4 4 of Fig. 1.

The main object of my invention is to provide a practical and efficient means of using 20 gas to heat a steam-boiler instead of the articles of fuel heretofore commonly in use for this purpose, and some of the advantages derived from my invention, which I am about particularly to describe, are, first, economy of fuel; 25 second, doing away with smoke in and about the heating of a boiler; third, saving in the wear and tear of boilers, inasmuch as the gas-flame keeps the boiler-sheets clean; and, fourth, in keeping the temperature underneath 30 the boilers at a more even heat by doing away with the necessity of constantly opening and shutting doors, which allow of cold air suddenly entering to the boilers, when there is a necessity of constantly replenishing the fires or cleaning 35 the under part of the boilers.

Like letters refer to like parts in the drawings wherever they appear.

The construction of my invention is as follows: A represents the boilers. There may 40 be as many of them or as few as desirable. Beneath these boilers A, and in such position as to leave a space underneath the boilers, are situated a number of air-pipes, B. These air-pipes are preferably flat in shape, as shown in 45 Fig. 4, the object being to construct them in the most suitable manner to carry air and at the same time present the greatest amount of heat-absorbing surface. These air-pipes B are connected at their ends b with an air-conduit 50 chamber, C, and at their other ends, b', air-

pipes B open into an air-chamber, D, which has preferably branch chambers d. Combustion-chambers E are situated immediately under boilers A, and preferably, as shown in the drawings, underneath the front end of boilers 55 A. These combustion-chambers E are surrounded, preferably on three sides, by the air-chamber D, before mentioned, and its branches d, and these combustion-chambers E are provided with port-holes e, by which connection 60 is had with the air-chamber D and its branch chambers d.

In the combustion-chambers E, preferably at the bottom of the same, are port-holes G, through which gas is admitted into the combustion-chambers. 65

From any suitable producer gas is led into combustion-chamber E through port-holes G, preferably in the following manner: A gas-conduit chamber, H, leads up to the opening 70 I in the valve-chamber K, and this opening I is closed or opened by means of the valve L. This valve-chamber K opens directly into gas-port hole G. Valve-chamber K is provided with a man hole or opening, M, which is kept 75 closed, except when it may be desirable to clean out or repair parts immediately about valve-chamber K. Owing, however, to the construction and arrangement of the valve I, valve-chamber K, and its man-hole M, and the 80 direct connection of the valve-chamber K with the gas-port G, the man-hole may be opened at such times as the valve I is closed, should it be desired for any purpose to admit cold air directly to the combustion-chamber E. 85

In the upper part of combustion-chamber E several suitable openings, e', are made, through which products of combustion will find their way, passing thence underneath the boilers A in the line of the arrows, indicated in Figs. 1 and 3, to a flue-opening in the rear, and thence to the outside air. 90

It will be noted that the air-chamber D d, into which the hot-air pipes B deliver, incloses the base of the combustion-chamber E on three 95 sides, and that the said sides are perforated below by air-ports e, which deliver the heated air in horizontal jets or sheets, through which the gas admitted through the gas-ports G in the bottom or lower part of the combustion- 100

chamber E is forced to rise, while the products of combustion escape directly below the forward end of the boiler through ports e' in the crown of the combustion-chamber as well as 5 from the throat of said combustion-chamber E.

The operation of my invention is as follows: A fire is first started in combustion-chamber E, and this fire is fed and increased by the fresh supply of the oxygen of the air admitted 10 from the pipes B through chambers D and d to the combustion-chamber E, and as the products of combustion pass out through openings e', underneath the boilers A and over the pipes B, these air-pipes B are heated, and at the same 15 time the heat radiated from the combustion-chamber E heats the air-chamber D and its branches d, and by the time the fuel used to start the fire in combustion-chamber E has become exhausted the air-pipes B and air-chambers D d are thoroughly heated, so that 20 the air being led from air-conduit C through pipes B to air-chambers D d enters combustion-chamber E through port-holes e in a condition to ignite gas. Valve L is then opened, 25 so as to allow gas in gas-conduit chamber H to pass up through openings I into valve-chamber K, and from thence through port-hole G into combustion-chamber E, and then, gas and air mingling with each other under the 30 conditions stated, combustion takes place, and my improvement is in full operation thus: The products of combustion are passing out through exit-openings e' of combustion-chamber along underneath the boilers A in the 35 direction of the arrows (see Fig. 1) to the flue, and at all times while this is going on the air-pipes B and chambers D d are being heated, thus providing a constant supply of heated air for the combustion-chamber. The number 40 of combustion-chambers E is regulated at will according to the number of boilers used; but wherever a combustion-chamber is used it must be connected, as shown, with the air-chambers and with the gas-producer, and it 45 must be provided with openings, through which the products of combustion may pass out and perform their proper office.

Among the great advantages derived from devices constructed and arranged substantially as hereinbefore set forth are the perfect manner in which the fires can be controlled by increasing or decreasing the relative supply of gas and heated air, the readiness with which the temperature can be lowered 55 or the fire damped by the admission of cool or non-heated air to the combustion-chamber, and the fact that when non-heated air is admitted it must first pass through the combustion-chamber and cannot strike directly on 60 the boiler-plates. Added to these advantages are extreme simplicity of construction with thorough effectiveness in operation.

I claim—

1. The combination, with a combustion-chamber having ports in its crown for the escape of the products of combustion, of an

air-chamber inclosing the base of said combustion-chamber and having ports for delivering air thereinto, air-pipes which deliver into the air-chamber, and a gas-supply port 70 which delivers into the combustion-chamber below the air-ports thereof, substantially as and for the purposes specified.

2. The combination, with a boiler having a smoke or waste-product chamber below it, 75 of an independent combustion-chamber arranged in the smoke or waste-product chamber, said combustion-chamber having a gas-supply below and ports in its crown for the escape of waste products, an air-chamber 80 which incloses the combustion-chamber and communicates therewith by suitable ports, and an air-supply delivering into the air-chamber, substantially as and for the purposes specified.

3. The combination, with a boiler having 85 a waste-product chamber below it, of a combustion-chamber having ports in its crown for the escape of products of combustion, said chamber arranged below the boiler and in the waste-product chamber, an air-chamber which 90 surrounds the combustion-chamber and has ports which deliver into the combustion-chamber, air-pipes arranged in the waste-product chamber below the boiler, and which deliver into the air-chamber, and gas-supply ports 95 which deliver into the combustion-chamber, substantially as and for the purposes specified.

4. The combination, with a combustion-chamber having an air-heating chamber surrounding it and ports of communication between the two chambers, of a gas-supply main, a valve for controlling the entrance of gas into the valve-box, a valve-box having a port or man-hole, as at M, and a gas-port leading from the valve-box and delivering into 105 the combustion-chamber, substantially as and for the purposes specified.

5. The combination, with a battery or plurality of boilers, of a series of independent combustion-chambers arranged in the waste-product chamber below the boilers, said chambers having crown-ports e', surrounding air-chamber D d d d, having ports e leading into the several combustion-chambers, air-pipes B B, arranged in the waste-product chamber 110 below the boilers and delivering into the air-chamber D, gas-conduit H, a series of valve-boxes, K, each having its port M, and gas-ports G, leading from the respective valve-boxes to the corresponding combustion-chambers, whereby the fire at various points under the battery may be damped and controlled at will, substantially as and for the purposes specified.

In testimony whereof I have affixed my signature, in presence of two witnesses, this 13th day of June, 1885.

MATTHEW P. ELLIOT.
